UNITED STATES PATENT OFFICE.

JAMES FREDERICK HODGETTS, OF LONDON, ENGLAND.

IRON-CLAD OR OTHER VESSELS.

SPECIFICATION forming part of Letters Patent No. 445,345, dated January 27, 1891.

Application filed May 13, 1890. Serial No. 351,605. (No model.)

To all whom it may concern:

Be it known that I, JAMES FREDERICK HODGETTS, residing at London, England, have invented an Improvement in Iron-Clads or 5 other Vessels, of which the following is a specification.

My invention relates to improvements in the construction of the hulls of iron-clads or other vessels, and is designed to provide increased resistance to submergence and greater 10 steadiness and stability in flotation, besides other advantages, hereinafter detailed.

Whereas the most ordinary form of sections of the hull of a vessel is round-bottomed or 15 of a peg-top shape, I have found by experimental trials that many advantages accrue to a vessel, especially when required for fighting purposes, by forming the bottom and bilge of the ship by means of a pair of catenarian 20 curves, each of the character produced by the suspension of a chain from points of different heights concave to the water (instead of the usual convex bilge) and springing from a central keel, dipping at each of the outer extremities 25 into side keels, parallel to the center keel and of about the same depth, these curves being of greater degree of curvature at or near the side keels than near the central keel. This pair of curves presents somewhat the 30 appearance of a pair of extended wings, such as those of the albatross, and although I specify these curves to be of the character of reverse catenarian curves, for convenient geometrical definition, similar curves may be employed—that is to say, any curve which springs 35 from the central keel with an easy curve of small curvature and dips suddenly with a terminal curve of increased curvature running nearly vertically into the side keels, and 40 such curves, being approximately similar to a catenary curve, though not an exact catenary in a strictly geometrical sense, may be used according to my invention. I have found that this particular form of bottom gives a practical 45 grip to the vessel of the bearing water, and thus tends to set in motion a large mass of water when the vessel tends to roll. The inertia, therefore, of the gripped volume of water would tend largely to check rolling.

50 The outline of the hull in section is such that the transverse dimension or average beam of the hull is considerably greatest at the water-

line, the submerged portion receding back to the outermost keel on either side and the upper works also receding from the water-line to the 55 bulwarks, and when protective armor is employed an inclined surface is presented to the impact of projectiles, and thus tends to deflect them.

It has further been found from experimental 60 trials that the special construction of the bottom of the hull, as above described, and with which may be combined spaces or pockets containing and retaining air, confers a great increase of buoyancy upon the vessel as compared with its apparent external displacement. This quality will therefore enable 65 such a vessel to carry a greater weight of armor and heavier guns than is possible in ordinary hulls of ships of like tonnage. Again, 70 my concave construction will provide an element of buoyancy after the external shell of the hull may have been pierced. Screws may be fitted to any of the said keels either fore or aft, which if, say four in number—viz., two 75 on each of the outside keels—will give extra assurance against total disablement of all propellers and will confer great advantages upon the vessel as regards steering. The position of the propelling-screws above described will 80 be such that they will be situated on the quarter and near the bows of the vessel, and would be thus protected by the overhanging bow and quarters of the said vessel.

In order that my invention may be the better understood, I now proceed to describe the same, reference being had to the drawings herewith, and to the letters marked thereon.

Figure 1 is a half-section of my improved vessel at amidships, showing the particular 90 outline of the vessel at this point and showing at one side outline sections toward the bow and in the other outline sections toward the stern. Fig. 2 is a profile view of my improved vessel, showing how and where the concave 95 arches gradually merge into the central keel at the stem and stern.

A is the central keel of the vessel, from which spring on each side of it the curved arches B B of a catenary or equivalent form, the arches B B terminating in the side keels c c. The sides 100 of the ship are formed of a glacis shape, as shown at D D, the face of such glacis being covered by armor.

The interior of the vessel is divided into water-tight compartments.

The propellers are shown in convenient positions at E.

5 Having now particularly described and ascertained the nature of my said invention and in what manner the same is to be performed, I declare that what I claim is—

10 The construction of the hull of a vessel with the bottom and bilge formed by a pair of curves, such as reverse catenarian curves, in the plane of the cross-section of the vessel concave to the water and springing from a

central keel with a curve of small curvature and dipping at their outer extremities with 15 curves of much curvature to side keels parallel to the center keel, substantially as described.

In testimony whereof I have signed my name to this specification in the presence of 20 two subscribing witnesses.

JAMES FREDERICK HODGETTS.
